UNITED STATES PATENT OFFICE.

LONNIE J. PAYLOR, OF DANVILLE, VIRGINIA.

TOBACCO-HANGING MACHINE.

Application filed October 23, 1920. Serial No. 418,979.

To all whom it may concern:

Be it known that I, LONNIE J. PAYLOR, a citizen of the United States, residing at Danville, in the county of Pittsylvania and State of Virginia, have invented new and useful Improvements in Tobacco-Hanging Machines, of which the following is a specification.

This invention relates to machines for hanging "hands" of tobacco although, of course, it could be readily used for the hanging of articles of a similar nature.

The invention deals more particularly with certain improvements in the machine disclosed in my Patent No. 1,362,893, granted Dec. 21, 1920, in which there is disclosed a machine comprising, broadly, a conveyor for hands by which the hands are carried gripped at their tied ends and supported in pendent position. The conveyor carries the hands against a spear point which penetrates the hand just below its tie leaf and forms an opening in the hand among its leaves. The machine is also provided with means for spreading apart the portions of hands on each side of the opening formed by the spear and for fluffing the hand so that the moisture in the drying machine into which it is subsequently introduced will thoroughly penetrate the hand. After the hand is thus fluffed and opened up it is carried by the conveyor, in this opened-up condition, to a discharge point where it is deposited upon sticks held at this point to receive the hands, the hands being placed upon the sticks in straddling position.

In the practical employment of the above described machine, which is disclosed in my patent referred to, it has been found that it is frequently necessary to remove and clean the spear point which forms an opening in the hand, due to the fact that gum and other matter of a similar character contained in the tobacco tends to collect upon the spear, thus blunting it and materially impairing its effectiveness.

It has also been observed that, due to the fact that when the hand is impinged upon the spear point it is gripped only at one end, its tied end, the remainder of the hand supported in pendent position, the spear does not always penetrate the hand at the proper point, there being a tendency for the hand to swing laterally and thus vary the relative points of penetration in the various hands handled by the machine. As will be

obvious to one skilled in this art, it is highly desirable that the hands be opened up at substantially their longitudinal center so that when they are placed upon the sticks they will be maintained in a state of equilibrium and thus not fall from the sticks.

The present invention has as its objects to provide means for preventing the formation of gum upon the hand penetrating member or spear point, improved means for gripping the hand as it is impinged against the stick, a novel and more satisfactory construction for the penetrating member, and finally, means for steadyng the hands as they are placed upon the sticks.

The above are the principal objects of the invention, and they and other objects of a more minute and obvious character will become manifest from a reading of the following detailed description in connection with the accompanying drawings, in which

Fig. 1 is a side elevational view of the forward end of the machine,

Fig. 2 is a side elevational view of the rear end of the machine,

Fig. 3 is a front elevational view of the portion of the machine shown in Fig. 1,

Fig. 4 is a plan view of a portion of the rear end of the machine shown in Fig. 2,

Fig. 5 is a side elevational view of the hand penetrating member,

Fig. 6 is a plan view of the penetrating member shown in Fig. 5, and

Figures 7 and 8 are cross sectional views on the lines 7—7 and 8—8 of Fig. 6.

In the views which have above been generally described I have shown one form of a device in which each of the several improvements hereinafter described in detail may be embodied, but it is to be understood that the showing in the drawings and the following description is merely for the sake of conveying a clear and comprehensive idea of my invention, which is not limited to the specific details shown, but which might be embodied in other forms without departing from its spirit and scope.

In the drawings I have shown only so much of the machine, shown in its entirety in my patent, as is necessary for a thorough understanding of the various features to which this application relates. In the drawings, 10 indicates the frame of the machine, which may be formed from any suitable material, such as steel or iron, and which may have vertical frame pieces 11 spaced apart

by cross bars 12 connected to the vertical pieces by any suitable means, such as the L-shaped brackets 13 and bolts 14. Between the frame pieces and supported upon the 5 longitudinally extending frame strips 15 and the cross bars 12 is the hand spreader and dividing member which, as set forth in my co-pending application, comprises, generally, a penetrating point 16, a vertically 10 or longitudinally dividing member 17 and rearwardly extending and diverging bars 18 which are formed with main or shank portions 19 running parallel from bends 20 through practically the entire length of the 15 frame of the machine. The spear point and spreaders are supported upon vertical legs 21 to which the spreaders are secured. The spreader and spear point are located below a conveyor which comprises the facing end- 20 less belts 22 which extend in a horizontal plane through the frame work above the penetrating member and spreaders and between two guides or presser members 23, 24. These presser members are each shown in 25 the device of this application as formed from two strips slightly spaced apart vertically and having therebetween idlers 25 which are disposed in the staggered relation shown in my co-pending application. 30 The guide or presser members are each supported upon arms 26 which are slightly spaced apart and are connected to upper frame cross bars 12' by means of angle bars 27 bolted to the arms 26 and to longitudinally extending strips 28, which strips are bolted to angle irons 29 secured by means of bolts 30 to the cross bars 12'. The guide or 35 presser members 23, 24 are urged together to press the belts by means of springs 31 40 which are supported and act in the manner disclosed in my co-pending application.

So much of the machine as has been already described is generally old, and is shown in my patent, although there are some 45 structural features which vary slightly from the identical device disclosed in my patent.

As described in my patent, the penetrating member 16 is detachably secured to a bar 16' extending longitudinally of the frame 50 beneath the traveling belts. Referring to Fig. 5, the penetrating member is provided with a reduced threaded shank 35 which fits into a socket in the bar 16'. The penetrating member is shown as being provided with 55 curved or arcuate lateral faces 36 which taper to a relatively thin flat tip. The lower or under face of the penetrating member is provided with a knife or cutting edge 37 which, as will be observed from an inspection of Fig. 5, curves longitudinally, and the upper or top face may be provided with a cutting edge 38 which may be comparatively straight. By forming the penetrating member as above described and 60 shown in the drawings, should the hand be 65

impinged thereupon so that the point of the penetrating member enters among the tied ends of the leaves or at the tie leaf, the tie leaf will be cut by the lower cutting edge 37 as the hand is carried forward in the ma- 70

chine. Referring to Figs. 1 and 3, it will be noted that immediately beneath the penetrating member, and slightly forwardly of the same is positioned a pair of wheels or pulleys 39 75 secured to the lower ends of shafts 40 extending upwardly and having bearings in brackets 41 connected to the transverse bars 12' of the frame. These pulleys or wheels may be constantly driven from any suitable 80 source of power (not shown) and serve to grip the hand at a point slightly below the point of penetration as it is impinged upon the penetrating member. It is, of course, understood that the tied end of the hand is 85 held between the traveling belts of the conveyor and thus, at the time the penetrating member is forming the opening in the hand, the hand is held both at its tied end and at a point below the point of penetration. In 90 the machine disclosed in my patent, the hand is supported freely in pendent position while it is being penetrated, but for reasons hereinbefore set forth, it is desirable that it be held temporarily at both sides of the point 95 at which the opening is formed.

In order to prevent the collection of gum and other foreign matter upon the penetrating member, any suitable means may be employed which will wash this member. In 100 the device shown in the drawings I have shown a pipe 42 extending horizontally in the direction of the spear point and having a nozzle 43 which serves to eject a fine stream of water or other washing fluid against the 105 spear point. The pipe may be provided with a valve 44 by means of which the volume of washing fluid ejected from the nozzle may be regulated. Of course, it will be understood that my invention is not limited 110 to the particular form of means shown for washing the penetrating member since other means could readily be employed for satisfactorily accomplishing this result.

Referring now to Figures 2 and 4, it will 115 be noted that the belts 22 have a discharge point E at which point they each move in opposite directions around pulleys 45 which may be constantly driven to move the conveyor belts. At 46 (Fig. 2) is indicated the 120 stick conveyor, the traveling chain 47 which carries the sticks being concealed by the channel bar through which it travels, but a portion of the same being shown at the left end of the figure where the channel bar is 125 broken away. As described in my patent this chain carrying the sticks passes beneath the discharge point of the conveyor and the opened-up hands are dropped thereon at this point. It has been found desirable to 130

provide some means whereby the hands will be steadied as they are dropped upon the sticks and will thus be prevented from falling to the side. To this end any satisfactory 5 form of steadyng means may be employed, but in the accompanying drawings this means is shown in the form of a pair of fingers 48 secured to the rear ends of the guide or presser members 23, 24, as by bolts 49, and extend downwardly and rearwardly along each side of the stick conveyor. Thus, as the hands are dropped upon the sticks each finger serves temporarily to steady the hands and functions in this manner until 10 the conveyor has moved the stick a considerable distance from the discharge point.

In view of the fact that the operation of each of the features herein disclosed has been completely described in connection with 20 the detailed description of the construction, it is thought unnecessary to again delineate the operation of these features or of the entire machine, which is completely disclosed in my patent referred to.

25 I claim:

1. In a machine of the class described, means for supporting hands of tobacco, and means for penetrating the hands comprising a member having a relatively sharp point 30 and a bottom knife edge.

2. In a machine of the class described, means for supporting hands of tobacco, and means for penetrating the hands comprising a pointed member having a knife edge 35 upon its under face, said edge being curved longitudinally of said member.

3. In a machine of the class described, means for supporting hands of tobacco, and means for penetrating the hands comprising 40 a pointed member tapering in width from its point in the direction of its shank and having a knife edge curved longitudinally of said member.

4. In a machine of the class described, 45 means for supporting hands of tobacco, and means for penetrating the hands comprising a pointed member tapering in width and thickness from its point in the direction of its shank and having a knife edge curved 50 longitudinally of said member.

5. In a machine of the class described, means for supporting hands of tobacco, a pointed member for penetrating the hands, means for causing relative movement 55 between said supporting means and said pointed member, and means for moistening said penetrating member to prevent the accumulation of gum thereon.

6. In a machine of the class described, 60 means for supporting hands of tobacco, a pointed member for penetrating the hands, means for causing relative movement between said supporting means and said pointed member, and means for directing a 65 stream of washing fluid against said pointed

member to prevent the accumulation of gum thereon.

7. In a machine for operating upon tobacco, a member adapted to penetrate the tobacco, and means for washing the penetrating 70 member to prevent the accumulation of gum thereon.

8. In a machine for operating upon tobacco, a member adapted to penetrate the tobacco, means for directing a stream of washing 75 fluid upon the penetrating member to prevent the accumulation of gum thereon.

9. In a machine of the class described, means for supporting a hand of tobacco by gripping it at its tied end, a pointed member for penetrating the hand adjacent its tie leaf, means for causing relative movement between the supporting means and said penetrating member, and means operative while the hand is being penetrated to 80 grip the hand at the opposite side of the point of penetration from its tied end whereby the hand is thus held temporarily on each side of the point of penetration.

10. In a machine of the class described, 90 means for supporting a hand of tobacco from its tied end in pendent position, a pointed member for penetrating the hand adjacent its tied end, means for causing relative movement between said penetrating 95 member and said supporting means, and means for gripping the hand below the point of penetration while it is being penetrated.

11. In a machine of the class described, 100 means for supporting a hand of tobacco, means for forming an opening in the hand, means for supporting a stick in position to receive the opened hand, means for causing relative movement between said hand supporting means and said opening means, and stick supporting means, whereby the hand is opened up and placed upon a stick, and means for steadyng the hand as it is deposited upon the stick.

12. In a machine of the class described, 110 means for conveying a hand of tobacco, means for forming an opening in the hand between its leaves, means for supporting a stick in position to receive the opened hand from said conveying means, and means on each side of the stick for steadyng the hand as it is deposited upon the stick by said conveying means.

13. In a machine of the class described, 120 means for conveying a hand of tobacco, means for forming an opening in the hand between its leaves, means for supporting a stick in position to receive the opened hand from said conveying means, and means for 125 steadyng the hand as it is deposited upon the stick by said conveying means, said steadyng means comprising a pair of fingers positioned adjacent the stick, one on each side of the stick.

14. In a machine of the class described, means for conveying a hand of tobacco, means for forming an opening in the hand between its leaves, means for supporting a stick in position to receive the opened hand from said conveying means, and means for steadyng the hand as it is deposited upon

the stick by said conveying means, said steadyng means comprising a pair of fingers positioned adjacent the stick, one on each side of the stick and partly above the stick. In testimony whereof I have hereunto set my hand.

RONNIE J. PAYLOR.
